UNITED STATES PATENT OFFICE

2,447,747

TEAPOT SPOUT LADLE

Max W. Goldberg, West Bend, Wis., assignor to
Modern Equipment Company, Port Washington, Wis., a corporation of Wisconsin

Application February 19, 1945, Serial No. 578,696

2 Claims. (Cl. 22—81)

1

This invention relates to improvements in teapot spout ladles.

Teapot spout ladles, as used in the foundry industry, are commonly constructed with a complete metal shell which is circular in cross-section and this shell is lined with fire-brick or other refractory material. Projecting from a side of the shell and extending substantially throughout the height of the ladle is a teapot type of spout. The spout has its own metal shell which is also filled with refractory material, and in said refractory material the pouring duct is formed. The duct extends downwardly from the upper end of the spout and communicates with the interior of the ladle by way of an opening near the bottom.

Due to the fact that the refractory material in the spout covers a substantial portion of the metal shell of the ladle proper, this portion of the shell is not exposed to the air; as is the rest of the ladle shell and heat is retained in this portion of the shell to an excessive degree and is not properly dissipated. As a result, this spout covered portion of the metal shell as well as the ring at the top of the shell frequently buckles from the intense heat of the molten metal and becomes distorted. In addition, due to the conduction of heat by the spout covered portion of the shell away from the refractory material of the spout an insufficient amount of heat passes into the refractory material of the spout. Thus, if the ladle stands too long before pouring, the metal in the spout may "freeze up" and necessitate a relining of the spout and a part of the ladle in order to repair the damage.

It is, therefore, a general object of the present invention to provide an improved ladle of the type described which is so constructed as to prevent the above mentioned buckling and distortion; and which is constructed to allow sufficient heat to pass into the spout so that the metal in the spout is kept in a fluid condition.

A more specific object is to provide a ladle as above described wherein that portion of the metal shell of the ladle which is covered by the spout is formed with perforations to materially reduce the capacity of said portion of the shell to receive heat and to conduct heat away from the spout. The portion of the ladle shell just referred to is preferably a separately formed perforated metal plate having its edges overlapping the edges of a vertical opening in the ladle shell.

A still further object of the invention is to provide in a ladle having a separately formed metal plate behind the spout structure, means permit-

ting expansion and contraction of said plate without breaking the fire-brick lining of the ladle or causing buckling of the plate. The said means preferably comprises inflammable spacer strips positioned between the vertical edges of the perforated plate and the adjacent portions of the fire-brick lining. These strips, as soon as the ladle is used, are quickly burned to charcoal by the intense heat and leave a vertical space adjacent to each edge so that there is room for expansion of the metal plate. Thus undue pressures are not exerted upon the plate or the fire-brick lining.

With the above and other objects in view, the invention consists of the improved teapot spout ladle, and all of its parts and combinations, as set forth in the claims, and all equivalents thereof.

In the accompanying drawings, illustrating one complete embodiment of the preferred form of the invention, in which the same reference numerals designate the same parts in all of the views,

Fig. 1 is a side elevational view of the improved ladle with part broken away and shown in vertical section;

Fig. 2 is a horizontal sectional view taken on the line 2—2 of Fig. 1;

Fig. 3 is a front elevational view with parts broken away and shown in section to illustrate the perforated plate and spacer arrangement;

Fig. 4 is a front view of the metal shell to be used in forming the ladle proper before the perforated plate and spout have been connected thereto; and

Fig. 5 is a plan view of the perforated plate alone. Referring more particularly to the drawings, the shell of the ladle proper is designated generally by the numeral 8 and this shell is formed of steel plate. The shell comprises an upright portion 9 and a bottom member 10 which is suitably secured to the lower edges of the upright portion. The upright portion 9 is circular in cross-section but the edges 11 and 12 of the sheet forming said upright shell portion terminates short of meeting to leave a space 13 therebetween as illustrated in Fig. 4. Fitted within the shell adjacent to the upper edge of the upright portion thereof is a metal ring 14. This ring is in the form of a complete circle and is welded or otherwise secured in position.

A separate plate member 15, formed of steel and having a plurality of openings 16, is bolted as at 17 with its edges overlapping the edges 11 and 12 of the upright portion 9 of the shell (see

Figs. 2 and 3). The lower edge 18 of the plate 15 terminates above the bottom of the ladle as is clear from Fig. 3.

The ladle is lined in the usual way with a plurality of layers of fire-brick, or other suitable refractory material designated generally by the numeral 19. The refractory material also covers the bottom of the ladle and fills in the space at the front of the ladle below the lower edge 18 of the plate 15. An opening 20 extends through the latter portion of the refractory material to communicate with the interior of the ladle just above the bottom of the lining.

Before the lining is inserted, wooden spacer strips 21 and 22 are inserted adjacent the vertical edges 23 and 24 of the perforated plate 15. These wooden strips are held in place by the lining after the latter is in place.

Surrounding the exterior of the shell portion 9 of the ladle is a metal band 25 having trunnions 26 projecting laterally therefrom.

The spout portion of the ladle is designated generally by the numeral 27 and it includes spaced metal side portions 28 which are welded to the edges 11 and 12 of the shell portion 9. The spout also includes metal front plates 29 which are bolted as at 30 to angles 31. The latter angles are welded to the side portions 28 of the spout at the outer edges thereof.

The spout is packed with high temperature refractory material 32 such as fire-clay and the pouring duct 33 is formed in the refractory material. This pouring duct has a flared upper discharge end 33', and has its lower end communicating with the opening 20 which extends through the side-wall of the ladle proper. There may also be vertical holes 34 extending through the fire-clay within the spout. These holes form vents to carry away excess heat. At the bottom of the spout is a curved plate 35 which connects with the bottom of the ladle proper.

Heretofore, the upright portions of the shells of teapot spout ladles were solid and there was no gap such as the gap 13 formed in Fig. 4. With this prior type of construction the intense heat in that portion of the metal shell which is covered by the spout, was not exposed to the atmosphere and there was a tendency for the heat to stay in the spout covered portion of the metal shell rather than pass to the refractory material in the spout. Furthermore, there was a tendency for the heat in this spout covered portion of the shell to be conducted laterally to air exposed portions of the shell, it being much easier for the heat to travel in this manner than to pass into the refractory material of the spout where heat is desirable in order to prevent a "freeze up." With the present invention, however, the use of the gap 13, which gap is filled in by a perforated metal plate 15, provides an arrangement wherein the capacity of the metal plate 15 to retain and conduct away heat is materially reduced because of the perforations 16. Thus more heat will pass into the refractory material of the spout and be carried off by way of the vertical vents 34. Furthermore, the perforations 16 in the plate 15 will minimize the possibility of the plate buckling by lowering the capacity of this portion to receive heat and by adding flexibility to the plate. By allowing heat to pass into

the spout, metal in the spout portion is maintained in a fluid condition.

In addition to the above, and in order to insure against buckling, the novel spacer strips 21 and 22 are employed. With the use of these strips, as soon as the ladle is employed in a foundry, the intense heat from the molten metal will burn out the strips leaving vertical spaces filled with charcoal. This allows for transverse expansion of the metal plate 15 without exerting undue pressure on the fire-brick lining to crack the latter. This also provides for expansion of the plate without danger of the plate buckling there being sufficient clearance between the bolt 17 and one or both sets of bolt holes to allow for such expansion.

While the use of a separately formed perforated plate 15 is preferred, nevertheless a number of advantages of the present invention can be obtained by merely perforating the usual ladle shell directly behind the spout.

Various other changes and modifications may be made without departing from the spirit of the invention, and all such changes are contemplated as may come within the scope of the claims.

What I claim is:

1. In a ladle, a main upright metal shell portion having upright edges which terminate short of meeting to form a gap in the shell, a teapot spout connected to said upright edges and projecting laterally from the ladle, and a metal plate spanning said gap in the shell and having edges overlapping said upright edges of the main upright shell portion and connected thereto, a lining of refractory material in said ladle covering the inner side of said plate, refractory material in the spout positioned against the outer side of said plate, said plate having a multiplicity of openings therein, and upright spacer strips formed of material which disintegrates with high heat positioned in the adjacent refractory material and against the upright edges of said perforated metal plate.

2. In a ladle, a main upright metal shell portion having upright edges which terminate short of meeting to form a gap in the shell, a teapot spout connected to said upright edges and projecting laterally from the ladle, and a metal plate spanning said gap in the shell and having edges overlapping said upright edges of the main upright shell portion on the inner side thereof and connected thereto, a continuous lining of refractory material in said ladle covering the inner side of said plate and shell, refractory material in the spout positioned against the outer side of said plate, said plate having a multiplicity of openings therein, and vertical spacer strips formed of material which disintegrates with high heat positioned within the ladle lining and against the upright edges of said perforated metal plate.

MAX W. GOLDBERG.
